Teletype Corporation, Chicago, Ill., a corpora-
tion of Delaware

Application September 16, 1937, Serial No. 164,146

2 Claims. (Cl. 175—21)

The present invention relates to methods of and accessories for winding electrical coils and particularly to a method and instrumentality for securing and lashing the final convolution of an electrical magnet or solenoid winding.

The main object of the present invention is to provide means for securing the last turn of an electrical coil so as to prevent its becoming short-circuited while affording a lasting anchorage means preparatory to the application of the outer coil wrapping.

Another object of the invention is to produce a back-lashing convolution of uninsulated wire without hazarding the adjacent convolutions to the possibilities of short circuiting or without having to provide upon the back-lashing convolution the special precautions of insulation sheathing to prevent short-circuiting of adjacent convolutions.

Electromagnets and other coil assemblies adapted to certain manufacturing practices are frequently terminated with stranded or woven wire leads which are soldered to the wire that comprises the major coil winding. Wire terminals of this type extend from the coil to be attached to a circuit and for securing they are covered with a sleeve of insulating material, doubled back, and back-lashed against unraveling. The present invention concerns itself with an improved method of securing the terminal convolutions of a coil having the features of economical construction, low manufacturing cost, but most important that of effecting a positive lashing means for the coil winding, which may thereafter be covered by the finish wrapper without presenting a bulge or protuberance but maintaining a smooth cylindrical contour of the coil.

This feature is particularly adapted to the so-called solderless lead type of coil winding. Its utility is of paramount importance to coils of this type because the lashing plate provides not only a means for anchoring the final convolutions against unraveling, but also, in cooperation with the wrapping, contributes appreciably towards relieving any strains which might be transmitted on through the solder connection between the coil wire of which windings of this type are conventionally made, and the stranded or woven wire of which the leads are made, as explained in U. S. Patent No. 1,764,592 issued to A. H. Adams.

For a more comprehensive understanding of the present invention, reference is had to the accompanying drawing and to the specification following hereinafter, in which like reference

characters indicate corresponding parts throughout.

The single figure which comprises the accompanying drawing is a perspective view of a cylindrical type magnet, a portion of whose finish wrapper has been torn away to reveal the disposition of the lashing plate and its adjacent convolutions.

A magnet winding is represented by the general character 11 comprising a soft iron core 12, the flanges 13 and 14 which together with an intermediate sleeve form the spool, and a plurality of superimposed layers of winding 15. The inner winding terminal lead may protrude from the assembly in any suitable manner and may be secured against unraveling by the superimposed lappings of wire 15. In the single figure of the drawing there is no specific illustration of the inner terminal since the improvement concerns primarily a manner of securing outer coil terminals. Nevertheless, it will be understood that the novel principles disclosed herein may have application elsewhere as well, such as, for example, in connection with inner coil terminals or intermediate coil terminals. The final or outer terminal lead which is improved in accordance with the teachings herewith proposed has secured to it a length of flexible wire preferably of the stranded type, indicated 17, which is left bare or with but its ordinary insulating coat of enamel. In the particular illustration, the principal winding 15, as viewed from the foremost end of the coil, has been applied in a clockwise direction. The final convolution, which preferably comprises the afore-described attached stranded lead, is doubled back in counterclockwise direction after being looped through one of the eyelets 19 in the lashing plate 21. The first reversal of the terminal lead is indicated 16. This length of wire extends in an opposite direction from the principal convolution 15.

The lashing plate 21 may be made of thin fiber or other suitable insulation material. Its proportions may vary in accordance with the particular type of wire and size of coil. A secondary eyelet 22 formed in the opposite end of lashing plate 21 receives the approaching portion of the reversed loop which has been indicated 18. The extreme end of the terminal wire is again doubled back, and the several elements comprising the terminating assembly are then made secure by having wrapped over them, together with the remaining portion of the coil 11, a sheathing material 23. The outer wrapper or sheathing 23 may be a fabric or other fibrous tightly drawn

jacket. It serves both as an electrical insulation and as a binder. In the latter capacity, it not only secures the general class of coil convolutions 15 against lateral displacement and unraveling, but also it compels the concluding turn or convolution to cleave to its subjacent and adjoining ones.

The extremity of lead wire 17 is extended to the periphery of the coil by providing a small opening 10 in the wrapper 23 or by leading the extremity of wire 17 around the edge of the wrapper 23 and adjacent the spool flange 14. A suitable adhesive which secures the wrapper material 23 in position serves also to anchor that portion of the wrapper 15 23 which covers the extremity of lead 17 against casual effort at unraveling or unwinding.

While the present invention has been explained and described in contemplation of a specific embodiment as indicated by the accompanying drawing, and by the following specification, it is to be understood that numerous modifications and variations may be made without departing from the spirit of this invention. Accordingly, it is intended not to be limited by the specific language 25 of the foregoing specification nor by the details of the accompanying drawing, except as indicated by the hereunto appended claims.

What is claimed is:

1. A method of forming and securing wire coils 30 comprising the steps of winding a principal coil consisting of a plurality of layers of convolutions

superimposed one upon another, extending the terminal of said wire through an eyelet opening of a lashing plate, reversing the direction of winding to effect a reversed convolution, extending said lead through an opposite eyelet opening of the lashing plate, continuing in the original direction of winding of the convolutions of said coil, and applying an enveloping sheathing onto the surface of said coil for binding together the outer layer of convolutions, said lashing plate, and said 10 reverse convolution.

2. An electric coil comprising a core, a spool associated with said core, a plurality of helically wound coil convolutions of wire turned about said spool in layers superimposed one upon another, and means for securing the convolutions of said coil against unwinding comprising a floating tie plate having endmost thereof a pair of oppositely disposed eyelets, a portion of said coil wire extended through one of said eyelets and doubled back upon itself to comprise a reverse convolution to said plurality of helically wound convolutions, then extending through the other eyelet opening of said plate and being again reversed and continuing in the principal direction 25 of winding of said coil, and sheathing means for wrapping said endmost convolutions and plate frictionally into engagement with its nether convolutions.
